UNITED STATES PATENT OFFICE.

JOHN G. ROSENGARTEN, OF PHILADELPHIA, PENNSYLVANIA.

DESIGN FOR A SERVICE-PIN.

56,383.

Specification for Design.

Patented Oct. 5, 1920.

Application filed July 24, 1918. Serial No. 246,604. Term of patent 3½ years.

To all whom it may concern:

Be it known that I, JOHN G. ROSENGARTEN, a citizen of the United States, residing at Philadelphia, in the county of Philadelphia and State of Pennsylvania, have invented a new and original and ornamental Design for a Service-Pin, of which the following is a specification, reference being had to the accompanying drawing, forming a part thereof.

The figure is a face view of the service pin showing my new and improved design.

I claim:

The ornamental design for a service pin, as shown.

JOHN G. ROSENGARTEN.
